UNITED STATES PATENT OFFICE

LOUIS A. GEBHARD AND CORRIE F. RUDOLPH, OF WASHINGTON, DISTRICT OF COLUMBIA, ASSIGNORS TO WIRED RADIO, INC., OF NEW YORK, N. Y., A CORPORATION OF DELAWARE

FREQUENCY CHANGING SYSTEM FOR RADIO TRANSMITTERS

Application filed July 31, 1929. Serial No. 382,421.

This invention relates broadly to high frequency signaling systems. More specifically this invention relates to frequency changing apparatus for high frequency signaling systems.

An object of this invention is to provide an arrangement whereby the signaling frequency of a high frequency signaling system may be readily changed from one channel to another channel.

Another object of this invention is to provide an arrangement whereby the signaling frequency of a high frequency signaling system may be substantially instantaneously changed from one channel to another channel which is displaced from the first channel by a relatively large portion of the frequency spectrum.

Still another object of this invention is to provide an arrangement in which switching devices cooperate with the frequency changing devices of a high frequency signaling system whereby additional inductance or capacity units are either connected into or disconnected from the oscillatory circuit of the signaling system.

A further object of this invention is to provide an arrangement in which circuit making and interrupting devices cooperate with the frequency changing devices of the signaling system for either connecting into or disconnecting from the frequency determining circuits of the signaling system, additional capacity and inductance units.

Still a further object of this invention is to provide an arrangement whereby at predetermined intervals of actuation of the frequency changing system of a signaling system, switching devices are actuated and additional inductance or capacity units are connected into the frequency determining circuits of the signaling system.

Other and further objects of this invention will be apparent to those skilled in the art to which this invention relates, from the following specification and the claims.

According to this invention a frequency changing system employing an inductance of the type disclosed in the copending application of Louis A. Gebhard, Serial Number

327,984, now Patent No. 1,818,816, issued August 11, 1931, for inductance systems, has incorporated therein a switching mechanism, operable simultaneously with the changing of the value of the inductance, for inserting into circuit with the inductance either another inductance unit or a capacity unit whereby the signaling system employing the frequency changing system constructed in accordance with this invention is enabled to rapidly change its operating frequency over a considerable range of frequency channels.

In a radio signaling system operating over a wide range of frequency channels, additional condensers and inductances must often be connected into circuit in order to obtain the range of frequency channels necessary. If, for example, it is desired to operate a signaling system in the 4000 kilocycle, 8000 kilocycle, 12000 kilocycle and the 16000 kilocycle frequency channels it is usually necessary to either connect an additional condenser in parallel with the condenser normally used in the oscillatory circuit of the signaling system or to connect an additional inductance in series with the inductance normally used in this circuit when operating in the 4000 kilocycle and the 8000 kilocycle channels in order to be able to operate the signaling system effectively in the 12000 kilocycle and the 16000 kilocycle channels. Previously this switching operation has been carried out by an independent control. This invention contemplates accomplishing this switching operation automatically in the wave changing operation.

Referring to the drawings briefly, Figure 1 illustrates a view in side elevation in partial cross-section of an embodiment of this invention; Fig. 2 is a cross-sectional view along the line 2-2 of Fig. 1; Fig. 3 is a cross-sectional view in front elevation of a modified form of this invention; Fig. 4 is a detail view of the switching mechanism; and Fig. 5 illustrates a circuit arrangement.

In Fig. 1 of the drawings reference numeral 1 designates a panel member which may be either of insulating material or of conducting material such as is employed for electrical

shielding purposes. Panel 2 of metal or insulating material is supported by the spacers 3 which are carried by the panel 1. A bearing element 4 is carried by the panel 2 for supporting the rotatable element 7. The beveled gear 6 is provided with a projecting portion 5 which is fitted into a hollow portion of the rotatable element 7. Another beveled gear 8, which is adapted to engage the gear 6, is mounted upon the shaft 9. An elongated and well machined bearing 10 is mounted upon the panel 2 for supporting the shaft 9. A gear 11 is mounted upon the shaft 9 for engaging the teeth 12 of the gear unit 13 which is mounted upon the shaft 14. The shaft 14 actuates an inductance wave changing unit 15. Upon rotating the shaft 14 the inductance-turn-engaging member 16 is caused to continuously, frictionally, engage the stationary turns 68 which are mounted upon the rods 18. The stationary threaded rod 65 engages set screw 66 carried in mounting member 67 whereon turn-engaging member 16 is mounted. Screw 66 slides in a longitudinal slot in shaft 14. As handle 49 rotates shaft 14, screw 66 slides longitudinally along shaft 14, and turn-engaging member 16 slides around the successive stationary turns 68 which are mounted on rods 18, facilitated by the movement of screw 66 and mounting member 67. A variable capacity unit may be employed in place of the inductance system 15 where it is desired to vary the capacity of the frequency determining circuit instead of the inductance. Rings 19 and 20 are mounted upon the rotatable element 7. Set screws 21 and 22 are employed to fixedly position the rings 19 and 20 with respect to the element 7. A pin 23 is positioned upon the ring 20 for engagement with the notch 24a in the end of the member 24 which is carried by the switching member 25 upon which is mounted the switch blade 26.

Contact members 27 and 28, for receiving the switch blade 26 and completing electrical circuit therewith, are supported in position by the members 29 and 30, respectively. Binding posts 31 and 32 are provided for the members 29 and 30. Panel members 33 and 34 of insulating material, are supported upon the panel 2 by brackets 36 and 37 which cooperate with the spacers 38 and 39 and screws 38a and 39a associated therewith. Spacers 35, 35', 41 and 41' of insulating material, are positioned between the panel members 33 and 34 for rigidly holding the panels together. Members 42 and 43 are supported by the panels 34 and 33, respectively for engagement with the switching member 24 and for serving as a bearing for the switching member. Springs 44 and 45 are attached to the bearing members 42 and 43 and the pins 46 and 47 which are positioned upon the arm 25 for causing the switching member 25 to suddenly establish or interrupt the electrical

circuit between the contacts 27 and 28 and the switch blade 26 when the actuating member 24 is moved past a certain neutral position. The operation of the switching mechanism is more clearly illustrated in Fig. 4. A lever 49 is mounted upon the shaft 14 for actuating the gear 13 and operating the inductance system 15. A dial 48 is mounted upon the shaft 14. A dial 50 is mounted upon the rotatable member 7. Conventional indications are registered upon the dials 48 and 50. A window 51 is provided in the panel 1 whereby the indications of the dials 48 and 50 may be viewed and the position of the inductance 15 and the pin 23 may be determined.

In Fig. 2 of the drawings a cross-sectional view in front elevation is illustrated. The dials 48 and 50 are partially broken away in order to more clearly illustrate the position of the gear 11 which coacts with the worm gear 13 in the actuation of shaft 9.

In the modification of this invention illustrated in Fig. 3, an additional switching unit B similar to the unit A is provided. The units B and C may be angularly displaced from the position of unit A as shown. The pin 23 mounted upon the ring 20 will not engage the actuating levers 52 or 53 but the pin 54 which is mounted upon the ring 19 will engage the levers 52 or 53 because they operate in different planes. Spacer members similar to members 38, illustrated in Fig. 1 are not employed in supporting switching units B or C, these units are consequently mounted directly upon the panel 2. If it is desired the spacers 38 may be eliminated from the supporting arrangement of switch A and the switch may be mounted directly upon the panel 2 in which case the pin 23 would pass through slot 24b in the member 24 while the pin 54 engages with the sides of the projection 24a. The pin 23 will cause the operation of either unit B or C. This arrangement necessitates the use of spacers 38 and 39 to cause proper alignment of slot 24a with pin 23.

A detail cross-sectional view of the switching mechanism taken along the line 4—4 of Fig. 1 is illustrated in Fig. 4. The switch blade 26 is shown engaging the contact 27. By actuating the pin 23 and moving the lever 24 the arm 25 is suddenly caused to rotate about the bearing 42 as an axis and the switch blade 26 caused to engage the contact 27a. The spacers 35, 35', 41 and 41' may be provided with sleeves of highly resilient material, such as rubber in order to reduce the shock to which the spacers may be subjected in the operation of the switch.

In operation the additional inductance or capacity unit to be connected into circuit or disconnected from circuit upon the actuation of the switch mechanism is connected to the switching mechanism. For example, as illustrated in Fig. 5, the terminal 56a of the ad-

ditional inductance unit 56 may be connected to the binding post 31a of the switch A, and terminal 55a of the inductance 55, which is already connected into the anode circuit of the shield grid electron discharge device 58 is connected to the terminals 32 and 32a. The positive terminal of the source of supply 57 is connected to the terminal 56b of the inductance 56 and the terminal 31. When the terminals 31 and 32 are connected by the switch blade 26 the inductance 55 is alone in circuit. When the terminals 31a and 32a are connected the additional inductance 56 is connected into circuit with inductance 55. 10 A similar arrangement is employed whereby an additional condenser 60 may be connected in parallel with the condenser 59 by the switching mechanism B. Terminal 61 of the switching mechanism B is connected to the condenser 59. Terminals 63 and 64 are connected to the condenser 60 which is to be connected in parallel with condenser 59. The terminal 62 is connected to the condenser 60 and the condenser 59. When the circuit 20 between the terminals 61 and 63 in the switching mechanism B is complete the condenser 60 is connected in parallel with the condenser 59. When the circuit between terminals 62 and 64 is complete the condenser 60 is short circuited. The inductance 55 may be controlled by the mechanism illustrated in Fig. 1 which is employed to control the switching devices A and B.

While we have described our invention in its preferred embodiment it is to be understood that many modifications thereof may be made without departing from the spirit and scope of this invention and that it is therefore intended that the foregoing specification is only for purposes of explanation and that no limitations other than are imposed by the scope of the appended claims are intended thereby.

What we claim as new and desire to secure by Letters Patent of the United States is as follows:

1. In a tuning system for covering a wide range of wave lengths, a shaft, a continuously variable inductance, a contactor rotatable on said shaft and engaging said inductance, a permanently connected condenser connected in circuit with said variable inductance, a fixed inductance, a fixed condenser, a toggle switch connected for connecting said fixed inductance in circuit with said variable inductance, a second toggle switch connected for connecting said fixed condenser in circuit with said permanently connected condenser, a rotating member, pins carried by said rotating member and positioned for respectively actuating said toggle switches as said rotating member is rotated, and a system of gears for transmitting rotative motion between said shaft and said rotating member, whereby the rotation of said

shaft connects said fixed inductance and said fixed condenser in circuit.

2. In a tuning system for covering a wide range of wave lengths, a helical inductance, a contactor slideable along said helical inductance, a rotatable shaft carrying said contactor, a permanently connected condenser connected in circuit with said inductance, a fixed inductance, a fixed condenser, a toggle switch connected for connecting said fixed inductance in circuit with said helical inductance, a second toggle switch connected for connecting said fixed condenser in circuit with said permanently connected condenser, a rotating member, pins carried by said rotating member and positioned for respectively actuating said toggle switches as said rotating member is rotated, and a system of gears for transmitting rotative motion between said shaft and said rotating member, whereby the rotation of said shaft connects said fixed inductance and said fixed condenser in circuit.

3. In a circuit arrangement, an electron tube having cathode, grid and anode, an input circuit connected to said grid, an output circuit connected to said anode, said output circuit comprising a continuously variable inductance and a permanently connected condenser, a fixed inductance, a fixed condenser, a shaft for varying said continuously variable inductance, a toggle switch connected for connecting said fixed inductance in circuit with said variable inductance, a second toggle switch connected for connecting said fixed condenser in circuit with said permanently connected condenser, a rotating member, pins carried by said rotating member and positioned for respectively actuating said toggle switches as said rotating member is rotated, and a system of gears for transmitting rotative motion between said shaft and said rotating member, whereby the rotation of said shaft connects said fixed inductance and said fixed condenser in circuit and tunes said output circuit.

LOUIS A. GEBHARD.
CORRIE F. RUDOLPH.
